United States Patent Office

Des. 184,744
Patented Mar. 31, 1959

184,744

FLOOR POLISHING MACHINE

George L. Lee, Bernardsville, N.J., assignor to Red Devil
Tools, Union, N.J., a corporation of New Jersey

Application May 20, 1957, Serial No. 46,230

Term of patent 14 years

(Cl. D9—2)

Figure 1 is a front elevational view of a floor polishing machine showing my new design;

Figure 2 is an elevational view of one side thereof, the other side being the same; and

Figure 3 is a rear elevational view thereof.

I claim:

The ornamental design for a floor polishing machine, as shown and described.
